SHIELDING SHOE FOR DRUMS AND
SIMILAR FILTERS

Nils Gustav Leffler, Sundsvall, Sweden

Application March 6, 1946, Serial No. 652,464
In Sweden January 12, 1942

24 Claims. (Cl. 210--199)

1

The present invention relates to filters of the type embodying a movable perforated filter member adapted to pick up on its one side solids from a suspension and to discharge suspension liquid at its other side after passage through the openings thereof under the influence of a differential pressure between said sides. Such a filter is usually, but not always, formed as a rotary cylindrical drum the peripheral surface of which is perforated and provided with a fine mesh wire fabric for picking up the solids of the suspension in which the drum is partially submerged, and wherein the differential pressure is produced either by evacuating the interior of the drum or subjecting the outer surface thereof to a super-atmospheric pressure. The invention is especially adapted for embodiment in rotary drum filters for picking up solids, such as fibers, powders and granules, from suspensions in liquids and is more particularly concerned with an improved construction of a shielding shoe for such filters.

It is an object of the invention to provide a shield shoe of the kind defined which will secure a sufficiently good sealing around that portion of the wire fabric where the taking off takes place. It is another object so to construct the shoe that it will in a high degree be independent of variations in said difference in pressure. It is also an object to provide means for pressing a sealing member of the shoe against the filter member at a constant pressure. A further object is to improve the sensitivity of the shoe, and a still further object is to provide a sealing shoe which will close off the take off portion effectively in filter drums even if the drum is not perfectly circular.

The invention will now be described more in detail with reference to the accompanying drawings illustrating various embodiments by which the invention may be realized in connection with vacuum drums for paper making but it is to be understood that the invention is not limited to the features so shown but has to be taken in its broadest scope.

In the drawings Fig. 1 is a cross sectional side elevation of the taking-off portion of a filter drum of the cell-free type and the shielding shoe according to the invention and Fig. 2 shows this shoe from the right, the drum being removed and a portion of the shoe being broken away to show details of construction. Fig. 3 is a cross section of the shoe along the line A—A in Fig. 1. Fig. 4 shows an alternative flexible connection between the stationary and the movable parts of the shoe. Figs. 5 to 7 show in the same way as Figs. 1 to 3, respectively, another embodiment of the inven-

tion and Fig. 8 shows an alternative means for securing the movable part of the shoe to the stationary one in the embodiment of Figs. 5 to 7.

The filter drum shown in Figs. 1 to 3 comprises a cylindric foraminous support 1 on the outer surface of which the wire mesh fabric, not shown in the drawings, is applied for taking up the solids suspended in a slurry of, for instance, cellulose fibers to form therefrom the fiber cake 6. At the take off position this cake will be removed by the doctor 5. The drum is rotated in the direction of the arrow in Fig. 1 and is submerged into the fiber suspension 7. The filter member 1 is according to this embodiment provided with flanges 2 connected to the disc-like ends 3 of the drum by means of bolts 4. The drum is in the usual way supported by hollow shafts or trunnions rotating in bearings outside the drum in the suspension vat which details are not shown in the drawings. The filtrate or liquid freed from fibers is withdrawn in the usual way from the interior of the drum through one or both of the trunnions to sucking tubes leading to a sealing tank.

At the taking-off portion of the filter where the doctor 5 is provided and downwards to the level of the suspension 7 the shielding shoe is arranged. The function of the shoe is to shut off the communication between the interior of the drum and the outer atmosphere partly for facilitating the removal of the cake and partly for preventing air from passing the naked portion of the filter member before the latter submerges again into the suspension. In the peripheral direction of the drum the shoe extends beyond this taking off place both ways and in the axial direction the shoe is substantially coextensive with the length of the drum or at least so as to cover all inward openings of the filter portion. As shown in the drawing the shoe is submerged into the filtrate 8 in the drum but this is not necessary for the satisfactory operation of the shoe. In filter drums having low filtrate exhaustion where, consequently, the filtrate level is low the shoe does not reach or submerge into the filtrate.

The shielding shoe consists principally of two main parts, the stationary shield member or support 9 being shaped and constructed so as to withstand the pressure differences encountered in vacuum filters, and the movable sealing member 10 being shaped and constructed substantially airtightly to close off the take-off portion and adjacent portions of the filter by sliding against and closing up the sieving or perforated section of the drum.

In the embodiment illustrated in Fig. 1 the support 9 and the sealing member 10 enclose a substantially liquidtight or airtight chamber 11 which communicates with the outer atmosphere or with a source of pressure medium (a gas or a liquid) by means of the conduit 12. So as readily and, if desired, controllably to secure the shoe to a bracket or the like, not shown, the support 9 is equipped with attaching feet 13 having borgings 14 for securing bolts. The brackets may be secured to a stationary shaft arranged in the centre of the drum. By turning this shaft, which may, if desired, be done during operation, the position of the shoe in the peripheral direction can be regulated according to requirements and running conditions.

The taking off portion of the drum being usually situated near the level of the suspension the shoe will usually have a vertical position. The sealing member 10 is pivoted about two pins 15 arranged in the axial direction of the drum at the lower end of the support 9, the holes receiving said pins in either the support 9 or the sealing member 10 being oblong in cross section with their elongated dimension extending substantially perpendicular to the support 9, i. e. radially of the drum. Being movable about these pins 15 to and from the filter member 1 of the drum the sealing member 10 can be resiliently pressed against sealing surfaces of the filter member, for instance by means of springs 16. In order to reduce the pressure against the filter or, if desired, to obtain a small interspace between the sealing surfaces of the shoe and the filter portion rolls 17 may be provided on the sealing part 10 pivoted about pins 19 in brackets 20 secured to the upper portion 21 of the sealing member 10 in such a manner that the rolls 17 will run along peripheral portions of the filter member outside its perforations. In order to facilitate the regulation of the position of the rolls in bracket 20 the pin shaft 19 is preferably so shaped that the axis of rotation of the roll 17 is eccentric to that portion of the pin 19 which bears in bracket 20 whereby the roll 17 can be moved in the radial direction of the drum simply by rotating the pin 19 more or less. By using for the roll 17 ball bearings the wear of the roll will practically be limited to its outer running surface and the wear of that surface will in any case be less than that of the sliding tightening portions of member 10. For diminishing the risk of jamming, the portions of the sealing member 10 sliding against the drum or the sliding surface of the drum may consist of or be coated with some suitable, relatively soft material such as hard rubber, soft rubber or artificial resin products. Along with the wear of roll 17 the sliding surfaces will then be successively ground so as to fit closely to the friction surface of the filter member independently of the wear of the roll.

In order further to insure a good sealing in the axial direction of the drum between the outer atmosphere and the interior of the drum, i. e. to prevent leakage of air into the drum by a flow axially along the surface of the sealing member 10 to the ends thereof and thence around the ends into the drum, the sealing member 10 may be provided with grooves 22 for housing sealing bars 23, which are resiliently pressed against the peripheral running path 18 of the filter member, for instance by means of springs 24. The bars 23 are preferably made from a material suited for water lubrication. In the embodiment shown in Fig. 1 the lower edge 25 of the

sealing bar 23 and the end of the groove 22 on which said edge rests are bevelled downwardly toward the surface 18 of the filter member so that the friction between the surface 18 and the bar will cause the latter to be wedged against the former.

For securing an efficient sealing between the support 9 and the sealing member 10 sealing rods 26 are movably provided in grooves 27 of the sealing member 10. Such rods are preferably provided at the upper part and along both sides of the sealing member. The grooves 27 may communicate with chamber 11 through hole 28 whereby the sealing rods will be exposed to the pressure prevailing in chamber 11 and, thereby be pressed against the sealing surfaces 29 and 30 of the support 9. It is, of course, possible to provide sealing rods also at the bottom of the shoe but in the embodiment shown in the drawing the contact surfaces 31 and 32 are preferably by being ground to each other arranged to seal sufficiently and effectively against each other. Said contact surfaces are preferably cylindric having their axis of rotation coinciding with the centre of the pivot pins 15.

Since the movement between the support 9 and the sealing member 10 is usually relatively small the connection between these parts may be carried out alternatively as shown in Fig. 4. A flexible plate 33 is liquidtightly or airtightly secured to the support 9 and the sealing member 10 by means of bolts 34. For preventing the bolt heads 34 from cutting down into the plate 33 ribbons 35, for instance of iron, may be interposed along the plate 33. By this means an absolutely airtight but nevertheless flexible connection can be obtained.

By providing a channel or the like 36 in the surface of the sealing member 10 facing the filter member at the upper portion of the shoe it is possible to connect that portion of the filter 40 having already been freed from the fiber cake and consequently been opened to the atmospheric pressure to adjacent portions still covered by the fibre cake and therefore still being under vacuum. 45 By this means the filter cake will be loosened beforehand and its removal by the doctor 5 will be facilitated. Although valuable in cell-free devices or apparatus of the kind shown in the drawings having a foraminous plate 1 for supporting the wire fabric said connection channel is much more important in cell filters where the shielding shoe slides against the inner portions of the various big cells or compartments into which the periphery is subdivided in that case. 50 By connecting the channel 36 with a source of pressure medium this effect can be further increased and the cake can be, so to say, blown away from the filter. For supplying pressure medium to channel 36 the pipe 37 is by means of flexible pipe 38 connected to the inlet nipple 39 of the channel 36. In case gaseous pressure medium is used in chamber 11 it will be sufficient to connect channel 36 with chamber 11 whereby the conduit 37, 38, 39 can be dispensed with.

60 In case the fluid or pressure medium in chamber 11 is water supplied through pipe 12 all seals between the support member 9 and the sealing member 10 can be made with relatively great clearance so that the different parts are more easily movable relative each other, because the leakage of water from chamber 11 to the interior of the drum will within certain limits not have any detrimental influence on the operation of the apparatus.

When the shielding shoe is submerged in the filtrate liquid the sealing will usually be sufficient at the lower end. Sometimes, however, some air may leak into the filter drum around the bottom of the shoe and for counteracting such leakage, particularly when the filtrate level is near or below the bottom of the shoe, water can be injected as by the perforated pipe 40 supplied with pressure water through pipe 41 either from outside or, as the case may be, from chamber 11. The perforations should be placed so that the injected water will be supplied to the place of leakage.

It often happens that the big filter drums are not exactly circular but are instead more or less irregular in shape. For eliminating, at least partly, this irregularity the inner portions of the sealing member 10 may, according to one embodiment of this invention, be made flexible or elastic. Thus the portion between the sealing details proper, that is, between the upper part 21 and the bottom part, for instance down to the pins 15, and between the grooves 22, may be made of flexible material such as thin steel plate. In a further development a flexible sealing member is secured about its entire periphery directly to the stationary member 9 and is then resiliently movable against the filter and performs its sealing function by abutting against the surface to be shielded off. Such a construction would be similar to that illustrated in Fig. 4, modified to the extent that the grooves 22, bars 23 and springs 24 would be omitted and the member 10 would be formed of a suitable flexible material.

In Figs. 5-8 another embodiment of the invention is illustrated. Whereas in the embodiment previously described the main members of the shielding shoe were hinged to each other at the bottom by means of pins 15 and sealing member 10 of the latter embodiment is movably connected to the support member 9 by means of a pair of arms 43 or 54, respectively, each of which connects, preferably, an intermediate point 42 of member 10 with a point 45 on the support member more or less at the end of the shoe, preferably at the upper end. The sealing member 10 of Fig. 5 is pivotally attached to arms 43 by means of the pins 42 and the other end of each arm 43 is pivotally secured to a bracket 44 on the supporting member 9 by means of the pin 45. By virtue of this mode of attachment the sealing member 10 is movable against the filter member 1 not only unilaterally about the pins 42 but through its entire length. It is, of course, possible instead to connect an intermediate point of the stationary member 9 with the upper or the lower end of member 10.

By replacing the pins 42 and 45 by round balls 46 and 47, respectively (Fig. 8), the sealing member 10 will be movable in all directions. The balls 46 and 47 are journaled in spherical bearings 48 and 49, respectively, having spherical covers 50 and 51, respectively, secured to the bearings by means of bolts 52 and 53, respectively. The balls 46 and 47 are connected to each other by the arm 54. Preferably two such connections are provided in about the same place as the arms 43 of Figs. 5-7, although a single connection of this construction positioned centrally of the shielding shoe would obviously enable substantially universal movement of the sealing member 10.

When water is used inside the shielding shoe leakage water may escape at the upper portion of the shoe and wet the dried fiber cake. For

protecting the latter a baffle 21 is provided at the top of the sealing member 10 preferably by shaping the top of that member adequately.

Apart from the hinging means characteristic to this embodiment the various details disclosed in connection with the description of the embodiment according to Figs. 1-4 may be applied to the present embodiment. Thus the various sealing bars 23 and 26 may be provided and runner rolls 17 can be used at the top as well as at the bottom.

In any of the embodiments the chamber 11 may freely communicate with the space between the sealing member 10 and the filter member 1 provided a substantially atmospheric pressure is prevailing in chamber 11.

Although particularly described in connection with filter drums submerged in a suspension of fiber it is to be understood that the invention can be employed equally well in conjunction with other types of picking up machines for suspended solids where these are picked up on a foraminous member by the action of a pressure difference between opposite sides of the foraminous member. Used in connection with filter drums in which the suspension is poured into the interior of the drum and the filtrate is drawn off outside by the aid of a lower outside pressure the shielding shoe of the present invention shall be arranged at the outer side of the drum and be shaped accordingly. Employed with cell filters in which the cells open at the one or both ends of the drum the shoe of the invention will be placed over an appropriate number of such cell openings at the end or ends of the drum.

As used in the specification and claims hereof, the words "seal" and "sealing" are not intended to apply solely to conditions in which a perfect seal is effected, because frictional seals are seldom, if ever, absolutely airtight or watertight. Instead, these words should be interpreted to mean that the leakage of air, water or other fluid is inhibited to the maximum degree practicable in structures of the character described, and that where the "seal" is made by frictional engagement between relatively movable members, a limited amount of leakage may exist without seriously impairing the utility of the invention.

What is claimed is:

1. A shielding shoe for filters of the type embodying a movable perforated filter member adapted to pick up on its one side solids from a suspension and to discharge suspension liquid at its other side after passage through the openings thereof under the influence of a differential pressure between said sides, said shoe comprising a stationary shoe member having walls forming a chamber having an opening facing said filter member, a sealing shoe member interposed between said filter member and said stationary shoe member and so supported by the latter as to be capable of limited movement relative thereto toward and away from said filter member, said sealing shoe member having an end wall at least a portion of which is adapted to engage one side of said filter member to shield off a limited number of the discharge openings therein and a peripheral wall portion juxtaposed to the wall portion of said stationary shoe member surrounding said chamber opening, and means for sealing the space between the juxtaposed wall portions of said stationary and sealing shoe members, whereby said members form an enclosure for the space within said chamber and that between the chamber opening and the adjacent portion of said filter member, the outer surface of said sealing shoe

member between the portion of the end wall adapted to engage the filter member and said sealing means having substantially no portion thereof exposed to an uncounterbalanced pressure component perpendicular to the filter member and arising from the atmosphere surrounding both shoe members.

2. A shielding shoe as claimed in claim 1 wherein in the area of said enclosure as projected on a plane substantially parallel to the filter member is substantially equal to that of the filter member engaging portion of said sealing shoe member as projected on the same plane.

3. A shielding shoe for filters of the type embodying a movable perforated filter member adapted to pick up on its one side solids from a suspension and to discharge suspension liquid at its other side after passage through the openings thereof under the influence of a differential pressure between said sides, said shoe comprising a stationary shield plate, a sealing member movable in a direction substantially perpendicular to said shield plate and having a restricted area of its outer surface adapted to engage one side of said filter member to seal off a limited number of the discharge openings therein, and means for sealing said shield plate and sealing member to each other to form a substantially watertight chamber between them, the outer surface of said sealing member between said sealing means and said restricted area being so shaped that all components of pressure exerted against said surface perpendicular to said restricted area are substantially counterbalanced.

4. A shielding shoe as claimed in claim 1 including means for supplying fluid under pressure to said enclosure.

5. A shielding shoe for filters of the type embodying a rotatable drum having a pervious filter member adapted to pick up on its one side solids from a suspension and to discharge suspension fluid at its other side after passage through the openings thereof under the influence of a differential pressure between said sides, said shoe comprising a stationary shield plate, an arcuate sealing plate supported by said stationary shield plate and adapted with at least the border portions of a restricted area thereof to engage one side of said filter member to seal off a limited number of the discharge openings therein, said sealing plate being movable relatively to said stationary shield plate toward and away from said filter member about an axis parallel to the axis of said drum, and means for sealing the space between the relatively movable edges of said plates, the geometrical projection of the area enclosed by said sealing means on the plane of said filter member being substantially equal to the geometrical projection of said restricted area on the same plane.

6. A shielding shoe as claimed in claim 5 including a pin fitted at one end of said stationary shield plate and forming a pivotal connection between the latter and said sealing plate.

7. A shielding shoe for filters as claimed in claim 6 wherein the shielding shoe is adapted to be mounted in a substantially vertical position and the pivot pin is located at the lower end of the stationary shield plate.

8. A shielding shoe as claimed in claim 5 including a pin parallel to the axis of said drum carried by said stationary shield plate at one end thereof, the adjacent end of said sealing plate having a hole in which said pin is received, the cross section of said hole being oblong with its

elongated dimension extending substantially radially of said drum.

9. A shielding shoe as claimed in claim 1 including pressure means in said enclosure for resiliently urging said sealing shoe member away from said stationary shoe member in a direction substantially perpendicular to the side of the filter member adapted to be engaged by said sealing shoe member.

10. A shielding shoe as claimed in claim 9 wherein said pressure means comprises at least one spring.

11. A shielding shoe as claimed in claim 1 including means for supplying a fluid under pressure to the enclosure formed by said shoe members for urging said sealing shoe member away from said stationary shoe member in a direction substantially perpendicular to the side of the filter member adapted to be engaged by said sealing shoe member.

12. A shielding shoe as claimed in claim 11 wherein the portion of the end wall of said sealing shoe member adapted to engage the filter member is provided with a depression of limited area lying wholly within the confines of said portion so as to provide a space between the depressed area of the shoe member and the adjacent side of the filter member, and which includes means for establishing communication between said space and the enclosure formed by said shoe members.

13. A shielding shoe as claimed in claim 11 including means for establishing communication between the enclosure formed by said shoe members and a restricted area of the portion of the end wall of the sealing shoe member adapted to engage the filter member.

14. A shielding shoe for filters of the type embodying a movable perforated filter member adapted to pick up on its one side solids from a suspension and to discharge suspension liquid at its other side after passage through the openings thereof under the influence of a differential pressure between said sides, said shoe comprising a stationary shoe member, a sealing shoe member interposed between said filter member and said stationary shoe member and so supported by the latter as to be capable of limited movement relative thereto toward and away from said filter member, said sealing shoe member having a wall adapted to engage one side of said filter member with at least the border portion of a restricted area of the outer surface thereof to shield off a limited number of the discharge openings in said filter member, said stationary shoe member having a rigid wall portion adjacent the periphery of said sealing shoe member, and means for sealing the space between said rigid wall portion of the stationary shoe member and the periphery of said sealing shoe member to shield the inner surface of the latter from the pressure of the atmosphere surrounding both shoe members, the outer surface of said sealing member exposed to said pressure being so shaped that all components of force exerted thereby against said surface in directions perpendicular to the filter member are substantially counterbalanced and the geometrical projection of the area enclosed by said sealing means on the plane of said filter member being substantially equal to the geometrical projection of said restricted area on the same plane.

15. A shielding shoe as claimed in claim 14 including rolls carried by said sealing shoe member adapted to run on running surfaces associated with said filter member.

16. A shielding shoe as claimed in claim 14 wherein said seal shoe member includes elongated sealing elements adjacent the edges thereof parallel to the direction of movement of said filter member and bordering said restricted area, and means for resiliently urging said elements outwardly from said sealing shoe member into engagement with said filter member.

17. A shielding shoe as claimed in claim 14 including means for connecting said sealing shoe member to said stationary shoe member for movement relative to the latter comprising at least one arm pivotally connected to both of said shoe members.

18. A shielding shoe as claimed in claim 17 wherein the pivotal connection of said arm to at least one of said shoe members is so constructed and arranged as to permit movement of said arm in a plurality of planes.

19. A shielding shoe as claimed in claim 14 wherein the portions of said sealing shoe member adapted to have engagement with said filter member are provided with sliding surfaces consisting of a relatively soft material, such as rubber.

20. A shielding shoe for filters of the type embodying a movable perforated filter member adapted to pick up at its one side solids from a suspension and to discharge suspension liquid at its other side after passage through the openings thereof under the influence of a differential pressure between said sides, said shoe comprising a stationary shield member having walls forming a chamber open at one side facing said filter member, a sealing member supported by said stationary shield member and movable relative thereto, said sealing member having a wall extending across the open side of said chamber and adapted to engage one side of said filter member to shield a limited number of the openings thereof from said differential pressure, and means for connecting said sealing member to said shield member and completing the closure of the open side of said chamber to render the latter substantially liquidtight, said means comprising a flexible strip of liquid-impervious material fixed both to the periphery of the wall of said sealing member and to said shield member.

21. A shielding shoe for filters of the type embodying a movable perforated filter member adapted to pick up at its one side solids from a suspension and to discharge suspension liquid at its other side after passage through the openings thereof under the influence of a differential pressure between said sides, said shoe comprising a stationary shield member having walls forming a chamber open at one side facing said filter member, a sealing member supported by said stationary shield member and movable relative thereto, said sealing member having a wall extending across the open side of said chamber and adapted to engage one side of said filter member to shield a limited number of the openings thereof from said differential pressure, and means for completing the closure of the open side of said chamber and rendering watertight the spaces be-

tween the relatively movable portions of said sealing and shield members including a groove formed in one of said members, a sealing element housed in the outer portion of said groove and projecting therefrom into frictional engagement with a cooperating sealing surface of the other of said members, and means including a conduit connected to the inner portion of said groove behind said sealing element for supplying a liquid under pressure to said groove to hydraulically force said sealing element into engagement with said cooperating sealing surface.

5 22. A shielding shoe as claimed in claim 14 including means for mounting said sealing shoe member for pivotal movement relative to said stationary shoe member about an axis substantially parallel to the direction of movement of said filter member.

10 23. A shielding shoe as claimed in claim 14 including means adjacent the end of the shoe where the filter member leaves the shoe for supplying liquid to the space between said end of the shoe and the filter member so as to prevent the leakage of air through said space.

20 24. A shielding shoe for filters of the type embodying a movable perforated filter member adapted to pick up at its one side solids from a suspension and to discharge suspension liquid at its other side after passage through the openings thereof under the influence of a differential pressure between said sides, said shoe comprising a stationary shield member having rigid walls forming a chamber of substantial area open at one side facing said filter member, an impervious flexible sealing member secured at its periphery to the walls of said stationary shield member and cooperating therewith to close the open side of said chamber and render the latter substantially liquid-tight, the flexibility of said sealing mem-

30 35 40 45

ber rendering it movable in a direction substantially perpendicular to said filter member, and means in said chamber for pressing said sealing member away from said shield member and into contact with one side of said filter member to shield a limited number of the openings thereof from said differential pressure.
